(57) **CLAIM**

The ornamental design for “a kit for hanging panel curtains,” as shown and described.

DESCRIPTION

FIG. 1 is a perspective view of a snap support for a curtain rod illustrating one component of “a kit for hanging panel curtains” in accordance with my new design;

FIG. 2 shows an elevational view, in perspective of the right hand side of the curtain rod with hook attachment in accordance with my kit for hanging panel curtains;

FIG. 3 is a perspective view illustrating a portion of the top, and left end thereof; and,

FIG. 4 is a perspective view of a hanger for panel curtains in accordance with my “kit for hanging panel curtains”.

FIG. 3 is shown fragmented for ease of illustration. FIGS. 1-4 depict elements of a kit for hanging panel curtains and are shown separately for convenient purposes only.
